ABSTRACT OF THE DISCLOSURE

A toy for manual operation comprising a handle, a string to be supported at one end by the handle and a number of balls fixed to said string near the other end thereof such that a rotating wrist action imparted to the handle will cause the depending balls to whirl in a plane passing through the ball fixed closest to the handle lengthwise of the string.

This invention relates to a toy and more particularly to a manually operated toy having balls fixed to a string for whirling motion.

There are known in the art numerous toys including one or more balls attached to a string. There is also known a toy comprising a hoop attached at the end of a string or a stick and adapted to perform a whirling motion.

It is an object of the invention to provide a new toy of the string and balls type wherein the balls are fixed to the string and are adapted to perform a whirling motion. Another object of the invention is to provide a toy of the string and balls type wherein the balls are symmetrically fixed at one end of the string lengthwise thereof.

A more specific object of the invention is to provide a small uneven number of balls fixed to a string and adapted to perform a whirling motion upon energization through a wrist action.

The invention will be described in detail by reference to the following description and appended drawings wherein is illustrated a preferred form of the invention and in which:

FIG. 1 is an elevation view of one embodiment of the toy in the motionless state.

FIG. 2 is an elevation view of the toy of FIG. 1 as seen in an arrested position of the normal operation state.

FIG. 3 is a perspective view of the same embodiment of the toy this time, as seen from the top when in motion.

The toy illustrated comprises a string or cord 1 on which are mounted and fixed a number of balls 2, 3 and 4 as shown in the drawings. As will be understood later, the number of balls is not limited to five as in the drawings. The end of the string 1 remote from the balls is threaded through a bore 5 extending through the bottom of a hollow handle 6 and a knot 7 at the end of the string 1 retains the latter in the bore 5 of the handle 6. The string 1 should be very flexible and free to rotate in the bore 5 of the handle 6. In order to do so, the knot 7 should be made small enough to rotate inside the hollow handle 6.

The whirling balls toy is operated by holding the handle 6 in a substantially vertical position with one hand, the balls and the string hanging down vertically from the handle and by imparting a rotary motion to the handle and the balls. After the balls have gathered some whirling speed, they move toward a horizontal position in the plane of the highest ball, in this instance, the upper ball 4. At that moment, as illustrated in FIG. 2, a very slight motion of the hand or fingers is sufficient to cause the

2

balls to adopt a planar whirling or orbiting motion. That is, the balls all rotate in the same plane passing through the uppermost ball, under the action of the centrifugal force acting on the rotating balls to produce a dynamic equilibrium. In FIG. 2, the ball called the uppermost ball is the ball 4 located on the left that is, the ball closest to the handle 6 lengthwise of the string 1.

In order to fully understand the particularities of the invention, I shall now describe certain characteristics related to the balls. As stated earlier, the number of balls is not necessarily limited to five. Any number of balls may be used, preferably an uneven number should be used and the number selected should be relatively low, such as 3, 5, 7 or 9.

Five balls appear to produce the optimum performance. An uneven number is preferred for when in whirling motion, the middle ball, ball 2, stays substantially motionless compared to the other balls which perform an orbiting motion around the said middle ball. This apparent substantially motionless middle ball produces a beautiful and amazing effect specially when multi-coloured balls are used. Another characteristic related to the balls is their disposition along the string and their choice. Basically, easily sustainable whirling motion will be obtained if the balls are symmetrically arranged lengthwise of the string in other words if the balls are symmetrically disposed and balanced relative to a middle position determined intermediate and respective to the group of balls. For example, if an uneven number of balls is used, the balls should be located symmetrically respective to the ball in the middle of the group. The balls do not need to be all of the same weight but the balls equally spaced from the middle ball or the point of symmetry should be of the same weight in order to achieve a uniform and stable whirling of the balls. For example, in the particular embodiment illustrated and described, the two balls 3 should have the same weight and should be equally spaced from the middle ball 2 and the same applies to the two balls 4.

The balls should preferably be multi-coloured. The balls are preferably made of rubber or other resilient material to avoid injury to the user or the bystander. The balls could equally well be made of any other rigid or semi-rigid material such as wood, plastics and metals. A bore extends diametrically across each ball and serves to thread the string therethrough. The balls are adapted to grip the string in order to fixedly position the balls on the latter. In the case of rubber and plastic balls, the bore may be made smaller than the string in order to provide the gripping action.

Any commonly used material such as wood or plastic may be used for the handle 6. The string or cord 1 must have substantial flexibility and must preferably be rotatably attached to the handle 6. In the embodiment illustrated, the knot 7 is loosely inserted in the bore of the hollow handle 6.

As can be seen in the drawings which illustrate a preferred embodiment of the invention, the ball closest to the handle along the string is preferably positioned midway between the ends of the string.

While a preferred embodiment of the invention has been specifically disclosed it is understood that the invention is not limited thereto as many variations will be readily apparent to those skilled in the art and the invention is to be given its broadest possible interpretation within the terms of the following claims.

What I claim is:

1. A whirling balls toy comprising a string, a handle attached to one end of said string, and a plurality of balls threaded in spaced apart relationship onto said string lengthwise thereof, said string passing diametrically through each ball and the centre of gravity thereof, each ball frictionally gripping the string to retain a spaced

apart fixed position along the latter, said balls being concentrated at the opposite end of said string relative to the handle and being constructed and arranged whereby a rotary motion imparted to the handle can cause the pending balls to whirl in a common and substantially horizontal plane.

2. A whirling balls toy as defined in claim 1, wherein the ball closest to the handle along the string is positioned substantially midway between the two ends of the string.

3. A whirling balls toy as defined in claim 1, wherein said balls are symmetrically attached along said opposite end of said string.

4. A whirling balls toy as defined in claim 3, wherein the number of balls in uneven and relatively low such that one ball is positioned in the middle with respect to the other balls lengthwise of the string.

5. A whirling balls toy as defined in claim 4, wherein each ball on one side of the middle ball has the same weight as the corresponding ball located on the other side of the middle ball at the same distance from the latter.

6. A whirling balls toy as defined in claim 5, wherein

all the balls are substantially equally spaced and of the same weight.

7. A whirling balls toy as defined in claim 6, wherein the string is rotatably attached to the handle.

8. A whirling balls toy as defined in claim 7, wherein there are five balls and the latter are made of resilient material whereby the resiliency of the material of the balls assures gripping of the string portions extending inside said balls.
